UNITED STATES PATENT OFFICE.

HENRY HARRISON SUPLEE, OF NEW YORK, N. Y.

INTERNAL-COMBUSTION ENGINE.

1,289,953.

Specification of Letters Patent. Patented Dec. 31, 1918.

Application filed March 21, 1917. Serial No. 156,238.

To all whom it may concern:

Be it known that I, HENRY HARRISON SUPLEE, a citizen of the United States, residing in the city, county, and State of New York, have invented certain new and useful Improvements in Internal-Combustion Engines, of which the following is a specification.

My invention relates to internal combustion engines and more particularly to a means of and method for controlling the temperature of the operating parts of the engine. My invention is especially concerned with the cooling of the cylinder, piston, and other parts which are exposed to the intense heat developed by the combustion of the fuel.

It is well known that unless the excess heat developed by the explosion and combustion of the fuel in the interior of the cylinder of an internal combustion motor is continuously removed therefrom, the temperature of adjacent parts will rise so high as to interfere with the operation of the motor, not only through carbonization of the lubricant, but also, directly, through overheating and consequent warping, burning, cracking and other injury to the material of the cylinder, piston, and other parts which may be exposed to such high temperature.

Heretofore, this excess heat has been removed by various well-known means, such as by the use of water jackets surrounding the cylinders and other parts; or by the rapid circulation of air about the exterior of the heated parts, this latter method including such extension of the surfaces exposed to the air as will aid in producing the desired effect.

These methods have been found fairly satisfactory for such parts as can be effectively reached by the cooling medium, whether water or air, but become inadequate when certain constructive limits of the parts are exceeded, or various modifications in design are introduced, by reason of the fact that the parts exposed to the high temperatures are not then all sufficiently close to the cooled portions to permit the excess heat to be removed as rapidly as it is produced; this

results in overheating, with all the accompanying disadvantages, as already set forth.

It is well known that the power of an internal combustion motor is increased by increasing the diameter of its cylinder, this increase giving an increased volume of combustible mixture to generate the power, and also providing a greater area of piston upon which the pressure of the expanding gases acts.

It has been found in practice, however, that the maximum diameter of the piston is dependent upon the limited rate at which the heat can be carried away from the middle portion of the piston mass to the cooled walls of the cylinder, and that when it is attempted to use pistons exceeding this maximum diameter the middle of the piston head becomes overheated and, hence, liable to fracture and other dangers.

My invention overcomes this difficulty by introducing into the interior of the cylinder, beneath and within the body of the piston, a system of air circulation, which effects an internal cooling and, by carrying the heat away directly, causes the cooling of the more central parts of the piston, at least, to no longer be dependent upon the conduction of heat through the body of the piston to its perimeter and thence to the cooled cylinder walls. This method of internal cooling also removes much of the heat from the inner surface of the cylinder itself, and thus relieves the external cooling system, whether by water or air circulation, from excessive demands which may be made upon it when the motor is operated continuously under heavy load.

It has also been found that in the special type of motors known as sleeve-valve motors, in which the admission and exhaust of the gases are controlled by one or more sliding sleeves concentric with the piston, the piston and inner sleeves are not so readily cooled as the parts which are in immediate contact with the exteriorly-cooled parts; this is because of the relatively low conductivity for heat possessed by the film of lubricant between the parts as well as by the necessary lack of molecular contact which results be-

tween any two masses of metal when a plane of cleavage is established between them. The maintenance of a continuous circulation of cold air within the interior of the inner sleeve, as well as within the interior of the piston, renders these portions, in a great degree, independent of the cooling circulation on the outside of the engine; and my invention is especially applicable to engines 10 of this type.

My invention will, perhaps, be more perfectly understood by referring to the accompanying drawings in which Figure 1 represents a cross section of the cylinder and 15 crank case of a conventional form of internal combustion engine, as arranged according to my invention and for the practice of the method thereof; and Fig. 2 represents a similar section of an internal combustion engine of the well known sleeve valve type, as 20 it appears with my invention embodied therein.

Referring to Fig. 1, A is the cylinder of the motor, in which the piston B moves with 25 an axially reciprocating motion, the combustion taking place above the piston B, and the motion being transmitted to the crank shaft by a connecting rod C, all in the usual well known manner. At D is shown an inlet 30 tube or pipe through which the air is delivered and at E is a similar pipe of somewhat larger diameter, through which the air makes its exit. These two pipes are firmly attached to the crank case F, and so 35 disposed as to avoid contact with the piston, crank, connecting rod and other moving parts of the motor, and are bent into the lower part of the cylinder in such a direction as to point toward the interior of the piston beneath its head. In the drawing the piston 40 is shown in its lowermost position, showing that the lengths of the pipes are such that the piston, at the limit of its stroke, comes down over them without touching or closing 45 the ends of the pipes.

The inlet pipe D is connected with a blower, pressure pump or other source of cold air, G, this blower or pump being preferably operated by the engine itself; or, if 50 the engine is used for automobile, aeroplane or like service, the source of cold air may be simply an inlet within the delivery of the usual air circulating fan of the engine or of the propeller of the aeroplane, or, the pipe 55 may be fed from the air current produced by the motion of the engine. It is desirable that a strainer I, be placed in the path of the incoming air, to intercept any particles of dirt which might otherwise enter the pipe 60 and, hence, the crank case, to the detriment of the operation of the engine.

The exhaust air pipe E, is preferably connected with an exhaust fan H, which draws the warm air out of the cylinder, or the pipe

may be permitted to discharge freely into 65 the outer air; or its discharge may be diverted to the carburetor of the engine or to any other part which it may be desired to warm.

The two pipes D and E, together with 70 means for delivering cool air and removing warm air from the interior of the cylinder, thus form an internal circulatory system, the amount of heat removed depending upon the 75 volume of air passing over the heated surfaces and the difference in temperature maintained between the air inlet and air discharge.

In order to avoid the removal of air 80 through exit pipe E before it has absorbed an adequate amount of heat from the cylinder and piston surfaces, *i. e.*, in order to avoid "short circuiting" the air current between the inner ends of the inlet and exit pipe, I preferably carry the inner end of 85 the inlet pipe nearer the piston head than the inner end of the exit pipe.

Furthermore, since the outgoing air has a 90 higher temperature and hence an increased volume as compared with the incoming air. I prefer to give the exit pipe a correspondingly larger cross section than the inlet pipe.

It is also possible, by such a circulatory system as has just been described, to introduce warm air into the interior of an engine, when necessary for any reason, such as the practice of aviation at high altitude, or in the operation of motors in unusually cold climates; so that my invention constitutes a 95 system of and means for internal temperature control.

It will be seen that when the piston is at the outward end or lowest limit of its stroke the discharge of cold air is delivered in a stream directly upon the under side of the 105 piston head, thus effectively removing the heat from that portion; and at all times the cold air is directed against this portion of the piston, hitherto most difficult to keep cooled. The exhaust air pipe is similarly 110 placed, so that the air which has abstracted the heat from the piston is continuously withdrawn, and it is the maintenance of this positive and continuous circulation which constitutes the method of cooling of my invention. The same conditions exist for the interior of the piston and for the interior of the sleeve or sleeves of a sliding sleeve-valve 115 motor as will be seen by examination of the embodiment of the invention shown in Fig. 120 2 in which parts corresponding to the parts shown in Fig. 1 are indicated by the same reference characters.

In this drawing the two sleeves I, J, which are provided with ports adapted to 125 register with one another and with the outlet and inlet ports in a manner well understood by those skilled in the art, are recip-

roated at proper times and as proper speeds by a half speed crank shaft K driven from the main crank shaft by chain or other suitable means (not shown). These 5 sleeves, in the embodiment here shown, completely encircle the cylinder. However, other forms of sleeve valve engines in which the sleeves only partially surround the cylinder, are well known; my invention is 10 equally applicable to such other forms without other change from the structure herein shown except such as would readily occur to those skilled in the art.

As will be seen from the drawing, the 15 piston and inner sleeve of this latter type of motor is thoroughly cooled by the interior circulation of cold air by my invention; whereas in the case of external cooling as heretofore, the heat generated in the interior of the motor must pass out by conduction through the mass of both sleeves as well as through two films of lubricant, before reaching the inner side of the externally cooled cylinder.

20 25 Owing to the fact that inlet and exit pipe both end at a level much higher than that of the oil in the crank case it is clear that, practising the method and with the apparatus of my invention, there is no danger 30 of forcing oil out of the crank case.

Having described my invention, I claim:—

1. The improvement in the art of regulating the temperature of internal combustion engines which comprises continuously 35 and positively removing air from regions adjacent to the interior of the cylinder and to the piston head and in continuously and positively replacing said air by other air whereby a continuous positive flow of air 40 over said surfaces is maintained.

2. The improvement in the art of regulating the temperature of internal combustion engines which comprises blowing air continuously directly upon the interior surface 45 of the piston head and in continuously removing said air by suction.

3. In an internal combustion engine, an air exit pipe fixed to the crank case and passing through the wall thereof the inner 50 end of the pipe lying within the cylinder and adjacent to the piston head, and exhaust pump connected to the outer end of the pipe, and means for admitting air to the crank case.

55 4. In an internal combustion engine, an air exit pipe fixed to the crank case and passing through the wall thereof the inner end of the pipe lying within the cylinder and adjacent to the piston head, an exhaust pump connected to the outer end of the pipe, and an inlet pipe also fixed to the crank case and passing through the wall thereof the inner end of said inlet pipe, like the inner end of the 60 exit pipe, lying within the inner sleeve and adjacent to the piston head.

the inner end of the exit pipe, lying within the cylinder and adjacent to the piston head. 65

5. In an internal combustion engine, a pair of pipes fixed to the crank case and passing through the wall thereof the inner ends of the two pipes lying within the cylinder and adjacent to the piston head, a compression pump connected to the outer end of one pipe and an exhaust pump connected to the outer end of the other pipe.

6. In an internal combustion engine, a pair of pipes fixed to the crank case and passing through the wall thereof the inner ends of the two pipes lying within the cylinder and adjacent to the piston head, a compression pump connected to the outer end of one pipe and an exhaust pump connected to the outer end of the other pipe, the cross section of the last named pipe being greater than that of the first named pipe.

7. The improvement in the art of regulating the temperature of internal combustion engines of the sleeve-valve type which comprises continuously and positively removing air from regions adjacent to the interior of the inner sleeve and to the piston head and in continuously and positively replacing said air by other air whereby a continuous positive flow of air over said surfaces is maintained.

8. The improvement in the art of regulating the temperature of internal combustion engines of the sleeve-valve type which comprises blowing air directly upon interior surfaces of the inner sleeve and upon the piston head and in continuously removing 100 said air by suction.

9. In an internal combustion engine of the sleeve-valve type, an air exit pipe fixed to the crank case and passing through the wall thereof, the inner end of the pipe lying 105 within the inner sleeve and adjacent to the piston head, an exhaust pump connected to the outer end of the pipe and means for admitting air directly to the interior of the inner sleeve.

10. In an internal combustion engine of the sleeve valve type, an air exit pipe fixed to the crank case and passing through the wall thereof, the inner end of the pipe lying within the inner sleeve and adjacent to the piston head, an exhaust pump connected to the outer end of the pipe, and an inlet pipe also fixed to the crank case and passing through the wall thereof, the inner end of said inlet pipe, like the inner end of the 115 exit pipe, lying within the inner sleeve and adjacent to the piston head.

11. In an internal combustion engine of the sleeve-valve type, a pair of pipes fixed to the crank case and passing through the wall thereof, the inner ends of the two

pipes lying within the inner sleeve and adjacent to the piston head, a compression pump connected to the outer end of one pipe and an exhaust pump connected to the outer 5 end of the other pipe.

12. In an internal combustion engine of the sleeve-valve type, a pair of pipes fixed to the crank case and passing through the wall thereof, the inner ends of the two pipes 10 lying within the inner sleeve and adjacent

to the piston head, a compression pump connected to the outer end of one pipe and an exhaust pump connected to the outer end of the other pipe, the cross section of the last named pipe being greater than that of 15 the first named pipe.

In testimony whereof I have hereunto set my hand.

HENRY HARRISON SUPLEE.
